UNITED STATES PATENT OFFICE.

WALTER S. FINNELL, OF CHICAGO, ILLINOIS, ASSIGNOR TO AMERICAN SCRUBBING EQUIPMENT COMPANY, OF CHICAGO, ILLINOIS, A CORPORATION OF DELAWARE.

MOP TRUCK.

Application filed May 26, 1920. Serial No. 384,396.

To all whom it may concern:

Be it known that I, WALTER S. FINNELL, a citizen of the United States, residing at Chicago, in the county of Cook and State of Illinois, have invented certain new and useful Improvements in Mop Trucks, of which the following is a specification.

The objects of the present invention are to improve the general make-up of a mop truck so as to facilitate the putting on and removal of the pails and also facilitate the handling of the mop when dipping it into the clean water pail and removing it therefrom; to provide for 10 the passing of the mop from the clean water pail to the wringer without permitting water to drop from it onto the floor; to provide for keeping the mop out of the dirty water in the other pail when it is being subjected to the action of the wringer; and to provide for a wide range of adjustment of the wringer to suit different sizes of mops.

In the accompanying drawings which form part of this specification Fig. 1 is a 25 perspective view of a mop truck embodying my present invention; Fig. 2 is a fragmentary perspective view illustrating a different adjustment of one of the wringer rollers from that shown in Fig. 1; Fig. 3 is a longitudinal section of the mop truck; and Fig. 30 4 is a partial end elevation.

The reference numeral 2 designates the metal angle bars forming the sides of the base of the frame of the truck, and 3 designates similar end bars and 4 designates cross-bars, and 5 designates wooden slats extending lengthwise of this frame base and secured to the end angle bars and to the cross-bars 4. At the front end the base is supported on swivel casters 6 and at the rear on wheels 7 journaled on a cross rod or shaft 8 secured to the undersides of the angle bars 2. The reference numeral 9 designates a wooden block secured to one corner of the base and serving as a foot-rest for steadyng the truck when the wringer is being operated. Uprights in the form of metal angle bars 10 rise from the rear corners of the base and other uprights in the form of metal angle bars 11 are bolted to the base side bars 2 near the front ends of the latter and incline away from the front of the truck. Upper side bars 12 connect the uprights 10 and 11, being also made of metal angle, and 55 on top of these upper side bars are bolted a

pair of angular metal cross pieces 13, one of which is located at the rear of the frame and the other of which is located a distance back from the front end of the said top side bars 12. The wringer is mounted between these 60 upper cross pieces as presently described. The frame is preferably stiffened at its rear end by cross braces 14 bolted to the corner uprights 10 and to each other where they cross.

A pan or basin 15 is suspended from the top of the frame below the cross pieces 13, being flanged to engage over the tops of the side bars 12 and conveniently clamped by the same bolts which secure said cross pieces to 65 said side bars. This pan or basin is made of galvanized sheet metal and the sheets forming the four sides thereof are flanged and united to form a hopper-like marginal portion of the bottom of the basin. The comparatively large central opening left by these 70 sloping bottom flanges 15^a is covered by a grille 16 secured against the undersides of said flanges. The bottom of the basin is at such an elevation as to provide for the ready 75 introduction and removal of the pail for the dirty water wrung from the mop.

In use the dirty water pail A will be placed directly below the grille of the basin, the purpose of which is to permit the free flow 80 of the dirty water squeezed from the mop C (Fig. 3) into the pail while keeping the mop itself out of the dirty water in the pail. It will be noted that the widely open character of the frame at its sides facilitates the ready 85 introduction of the pail and its removal. The clean water pail B is put on at the front of the truck where the frame of the latter is fully open. Inasmuch as the mop will be constantly dipped into the clean water pail 90 and removed therefrom in various directions it is important that there be free space well around the pail and it will be noted that the present construction amply provides for that. Thus the uprights 11 are secured to 95 the base back from the front end thereof and incline away from the front as they extend upward so that the space will be entirely free around the greater portion of the top part of the pail while at the same time the 100 pail will be so far between the uprights as to prevent its accidentally shifting position sidewise and falling off the truck.

It will be understood that for the purposes of rinsing the mop it will be dipped into the 110

clean water pail and then passed to the wringer. In such case it is desirable that any drip from the mop shall be prevented from reaching the floor. I therefore arrange a guard or shield in the space between the wringer and that part of the truck occupied by the clean water pail. This I make out of a sheet of galvanized metal flanged to engage over the forward portions of the top side bars 12, being secured thereto by screws 20. The guard or shield comprises a flat portion 21 having a bead which lies closely adjacent the forward cross piece 13, said portion 21 extending downward on a sharp inclination to a point between the inclined uprights 11 and over the area occupied by the clean water pail. The shield has sides 22 with forward edges inclined to correspond with the inclination of said uprights 11, and it is formed with a substantially vertical transverse portion 23 of concavo-convex form, being re-entrant with respect to the sloping portion 21. This formation of the guard or shield provides for substantial conformity with the circle of the top of the pail when the latter is properly positioned, and it will be seen that a mop dipped in the pail can be drawn out over the shield to the wringer without dripping onto the floor, any water falling from the mop during this procedure being caught by the shield and conducted back to the clean water pail. The aforesaid bead is here shown as formed by bending an extension of the adjacent side of the basin 15 over the upper edge of the guard plate 21—as at 15^b.

Referring now to the wringer, which as before stated is mounted between the cross pieces 13, the numerals 30 and 31 designate the wringer rollers, the former of which is plain and the latter corrugated, and 32 designates a rocker piece which is journaled in appropriate openings near the ends of the cross pieces and the operation of which by throwing its handle back and forth opens and closes the wringer in a well known manner. Thus the rocker piece has end arms 33 which cross center and are connected with springs 34 that embrace the journal rod or axle of the roller 30. The uprights and relatively high flanges of the angle cross pieces 13 are slotted longitudinally and metal heads 35 for the said roller 30 and in which its journal rod turns, are formed with ribs 36 which fit the slots 13^a and slide back and forth in them when the handle of the rocker piece is worked. The other wringer roller 31 is secured to a journal rod 37 which turns in metal heads 38 also provided with ribs 39 to fit in the slots of the cross piece flanges, but this other and corrugated roller is to occupy a fixed position, the wringer-operating crank 39 being fastened to its journal rod. It will of course be understood that the

swinging outwardly of the handle of the rocker piece carries the roller 30 away from the roller 31 and opens up a wide space for the receipt of the mop, and that when said handle is swung inwardly and down the mop is squeezed between the two rollers so that when the crank is turned the mop will be properly wrung.

Mops vary a good deal in size and character and so it becomes necessary to provide for varying the relationship between the rollers to suit different conditions. To meet this situation I provide for four adjustments of the roller 31 in the slots of the cross pieces; thus in the bottoms of the slots I provide square notches 40, two for each slot, and spaced apart to provide for two different settings of the roller. Then on the underside of each of the ribs 39 of the roller heads 38 I provide a lug 42 located to one side of the center of the roller. By this expedient I provide for doubling the number of adjustments of the roller, for it will be seen that by reversing the heads, i. e., interchanging them, the lugs 42 will come on opposite sides of the center from what they were before and consequently when engaged with the notches will differently locate the roller. As illustrated in Fig. 1 the lugs are forward of the center of the roller and engage with the notches further back and this setting is suitable for the largest mops. In Fig. 2 the other extreme is illustrated, the lugs being engaged with the other pair of notches and the roller heads having been reversed or interchanged so as to bring the lugs on the opposite side of the center. Obviously two intermediate adjustments of the roller are provided for, one of which would be established by engaging the lugs with the forward pair of notches as the structure is viewed in Fig. 1, the lugs being on the forward side of the center of the roller, whereas the remaining adjustment will be established by engaging the lugs of the reversed or interchanged heads with the other pair of notches, referring to the Fig. 2 illustration. It will be noted that these adjustments are not at the will of the user of the truck, but that the appropriate adjustment will be established in the assemblage of the parts,—given the size and character of the mop to be used.

I claim:

1. A mop truck comprising an open-sided frame adapted to carry pails in tandem, an elevated wringer basin over that portion of the frame which holds one of the pails, said basin having an open work bottom and a roller wringer mounted above said basin so that the mop passing down through the wringer may descend a distance within the basin and be received upon the open work bottom thereof.
2. A mop truck comprising an open-sided

frame adapted to carry pails in tandem, a wringer mounted over that division of the frame which contains one of the pails, and a shield between the wringer and the division of the frame which contains the other pail over which shield the mop passes from the latter to the wringer.

3. A mop truck comprising an open-sided frame adapted to carry pails in tandem, a wringer mounted over that division of the frame which contains one of the pails, and a shield extending obliquely between the wringer and the other division of the frame and concaved to conform to the clean water pail therein.

4. A mop truck comprising a frame base and corner uprights and side and cross top bars, the uprights at one end extending obliquely to give free access to a pail rest-

ing on the base between them, the frame being entirely open at this end for the placing on and removal of the pail, and fully open at the side for the putting in and taking out of another pail; and also comprising a wringer mounted between cross bars of the frame over the division of the frame which holds said pail, and a basin suspended from the top of the frame below the wringer and having an openwork bottom.

5. The combination with a pair of longitudinally slotted frame bars having notches opening into the slots; of a wringer roller and interchangeable bearing heads therefor each having an off-center lug adapted to selectively engage a notch of either of the bars.

WALTER S. FINNELL.
